UNITED STATES PATENT OFFICE

2,351,976

AUTOMATIC FIREARM

Josef Koucký, Brunn, Bohemia; vested in the
Alien Property CustodianApplication December 6, 1939, Serial No. 307,807
In Czechoslovakia December 10, 1938

2 Claims.

(Cl. 42—3)

My invention relates to automatic firearms which have a breech block actuated and controlled by a breech block carrier.

It is an object of this invention to provide for such a weapon of simple construction which is especially suitable for automatic rifles.

It is another object of my invention to provide for such a weapon which consists of a relatively small number of parts.

Other objects of the invention will appear as the specification proceeds.

According to the invention a recuperator spring is so arranged in connection with the breech mechanism of the firearm as to actuate the movements of the striking member of the firing pin and also to actuate, during the forward movement, the breech block carrier until the locking position of the breech block is reached.

By thus using the recuperator spring for two functions I obtain a weapon of simple design, the individual parts of which may be large whereby the strength and the precision of operation of the weapon are increased.

Preferably the striker is mounted on the breech block carrier and so arranged as to transmit, during the forward movement, the force of the recuperator spring to the breech block carrier, and to be actuated by the same spring for its striking movement at the end of the forward movement of the breech block. In this manner the action of the striker depends directly on the position of the breech block carrier, so that a premature firing with unlocked breech block or a belated firing with prematurely opened breech is prevented.

According to a preferred embodiment of the invention the striker may have the form of a lever which is hinged by one end to the breech block carrier, while its other end cooperates, before the end of the forward stroke, with a stop about which the striking lever tilts so as to recede relative to the breech block, while during this relative receding movement the breech block carrier finishes its forward stroke and simultaneously locks the breech block. Preferably this stop forms part of the sear, which is actuated by the trigger with the aid of a connecting rod.

In the drawing affixed to this specification and forming part thereof a self-charging rifle embodying my invention and provided with a tilting breech block is illustrated diagrammatically by way of example.

In the drawing:

Fig. 1 is a longitudinal section of the rifle with the parts in firing position.

Fig. 2 shows, on an enlarged scale, the cocked striker mechanism before firing.

Referring to the drawing, 1 is the breech case, 2 the barrel, 3 the trigger case and 4 the butt. The cases 1 and 3 are connected by means of bolts 5 and 6.

In case 1 the breech mechanism is arranged for free sliding movement. It consists of the breech block carrier 7, the tilting breech block 8 and the hammerlike striking member 9 to which latter is attached, by means of stud 10, the recuperator rod 11, the rear end of which rests on an abutment member 12 acted upon by the recuperator spring 13, which is arranged in the tube 27 held in the case 3 by the butt 4. The striker 9 is a lever, hinged to the breech block carrier 7 by means of the pin 24 and formed with a head 23 acting on the firing pin 31 accommodated in the breech block. 32 is the extractor for the empty cartridge cases.

The breech block carrier, which is formed with a tooth 29, cooperating with the tongue 30 of the breech block 8, is connected with the piston rod of the gas pressure loading-device (not shown). In the locking position the breech block 8 abuts against a cross piece 34 below which is removably arranged, the ejector 35, which, during the movement of the breech block 8, passes through a longitudinal groove 36 in the bottom face of this block. The ejector is held in the active position by the spring 37 of the lever 38 locking the magazine 19, which is a three-armed lever, the arm 38' being applied against the magazine 19, while arm 38'' serves for operation, and arm 38''' is the supporting arm.

41 is the ejector opening, through which the magazine 19 may also be filled with cartridges from belts.

The trigger mechanism comprises the forked trigger 16 pivoted to pin 17. Both arms of the fork carry at their ends locking teeth 18, which serve for locking the manually cocked breech block carrier 7, during the filling of the cartridge magazine 19 from belts or during an exchange of such belts. The trigger 16 is connected by means of a connecting rod 20, arranged between the arms of the fork, with the sear 21 extending into the path of the end of the striking hammer 9. Sear 21 is free to rotate about stud 6 and is acted on by spring 22. The entire trigger mechanism is acted upon by spring 25 which surrounds a guiding bolt

26 extending through an aperture in a short arm of the connecting rod 20.

In the case 3 of the trigger mechanism is arranged a stop 14, acted upon by the spring 15, free for displacement on the connecting stud 5. 5

The weapon operates as follows:

When a shot is fired, the gas pressure acts upon the piston which is connected with the breech block carrier 7 and drives it rearwards. During this movement the tooth 29 of the breech block 8 carrier 7 grips the nose of the breech block 8 lifting it from the locking position, whereby the breech block 8 is disengaged from the cross piece 34 and is carried along by the breech block carrier 7 which compresses the recuperator spring 13 by 15 way of the striker 9, the recuperator rod 11 and the abutment member 12. Just before the rearward movement has come to an end, the ejector 20 ejects the empty cartridge case through the ejector opening 41. The complete damping of the rearward movement of the breech mechanism is effected by the stop 14.

The breech mechanism, under the action of the compressed recuperator spring 13, now advances, 25 while a fresh cartridge is shifted into the cartridge chamber of the barrel 2. The breech block being continuously engaged by the breech block carrier 7 is driven forward by its cam faces, while the striker hammer 9 is entirely turned down, as shown in Fig. 1, with its lower end projecting behind the breech block. Before the forward movement has ended, the projecting end of the striker 9 engages the stop formed by the lever-shaped sear 21, which with its arm 21' rests on the wall of casing 3. At this moment the striker begins to act as a one-armed lever resting on the sear 21 and is tilted by the action of the recuperator spring 13 into the position shown in Fig. 2. During this movement the breech block carrier 7 finishes its forward movement, during which the cam face 42 moves the breech block 8 into the locking position wherein it rests on the cross piece 34. The head 23 of the striker 9 recedes during this movement from the firing pin 31, and the striker is cocked. On pulling the trigger 16, the sear 21 is tilted by the action of the connecting rod 20 counter to the action of the spring 22 so as to release the striker 9 which, under the pressure of the recuperator spring, tilts about the pin 24 until head 23 strikes the projecting end of the

striker 21 and thus effects the firing of the cartridge. Now the breech block carrier starts on its rearward movement, during which it releases the breech block, while the free end of the striker 9 slides along the cam face 21'' of the sear, which is tilted against the action of the spring 22. A slit 46, through which passes stud 47 of the trigger, allows the connecting rod 20 to be shifted during this tilting movement. The breech block carrier thereupon finishes its rearward movement, and the whole procedure is gone through once more.

The weapon described above and illustrated in the drawing is only an example of the invention, and the details, for instance the arrangement of the breech and trigger mechanisms, may be varied in various respects within the scope of the invention.

I wish it to be understood that I do not desire to be limited to the exact details of construction shown and described, for obvious modifications will occur to a person skilled in the art.

I claim:

1. An automatic firearm comprising in combination a breech case, a breech block carrier mounted to reciprocate backward and forward in said case, a breech block movable by said carrier between a locked and unlocked position while said carrier is traversing a forward portion of its path of movement, and movable with said carrier during the remainder of its movement, a firing pin mounted in said block, a striking lever pivoted on said carrier and having a striking portion arranged to strike said firing pin, means for moving the carrier backward on firing, means for moving said carrier forward and for actuating said striker comprising a recuperator spring and a connection between said spring and striking lever at a point of the lever removed from its pivot, said case being formed with a stop engaging the forward part of the free end of the striking lever when the breech block is in locked position.

2. The firearm set forth in claim 1 wherein said stop serves as a locking means and is provided with a forward locking face along which said breech block is moved by said carrier toward locked and unlocked positions.
